UNITED STATES PATENT OFFICE

ARNOLD SCHMID, OF VIENNA, AUSTRIA; HANS SCHMID AND IRMA SCHMID, ADMINISTRATORS OF SAID ARNOLD SCHMID, DECEASED, ASSIGNEES TO KARL SCHMID, OF MANNHEIM, GERMANY

PROCESS OF WASHING NITROGLYCERINE AND SIMILAR ESTERS

Application filed January 25, 1928, Serial No. 249,475, and in Germany February 5, 1927.

The object of the herein-described process is to effect the washing of the esters formed during the nitration of glycerine, glycol and similar alcohols in a continuous operation and in a simple reliable manner for the purpose of completely removing the last traces of acid.

A process is known wherein nitroglycerine is freed from the acid dissolved therein by a continuous washing operation but this is only possible by using a large number of washing vessels.

Nitroglycerine has, for instance, a very good dissolving capacity for nitric acid and therefore retains the last traces of the acid so that even if a soda solution is used as the washing agent, the washing operation occupies a great deal of time and a thorough stirring must take place. When carrying out the known process liquid eddies are always formed in the washing vessel whereby the portions of the acid nitroglycerine are carried along before they are deacidified. These portions are again mixed with deacidified nitroglycerine and naturally damage a great part thereof.

The present invention resides in the fact that the acid nitrating product is first emulsified by a thorough mixing with the washing agent and then this emulsion is led slowly on a long path while avoiding whirling motions which might bring the acid nitrating product in contact with the deacidified product, so that the washing agent has time to dissolve the acid out of the finely divided nitrating product and there is a large space between the place where the acid nitrating product is emulsified with the washing agent and the outlet for the deacidified product. The emulsion must remain on the entire path on which it is moved. Means must also be provided for preventing a whirling motion in the direction of the movement of the emulsion, that is to say, mechanical means must be used to prevent

the unwashed product at the emulsifying place from being carried into the washed emulsion.

If a vertical cylinder is used for carrying out this process, the acid nitrating product passes with the washing liquid into the lower part of the cylindrical chamber and the emulsification takes place by means of a thorough agitation. This may be effected by rotating vanes and preferably by the admission of compressed air. The unobstructed ascent of the whirled liquids in the cylinder must be prevented. This is attained by providing numerous sieve-like or perforated plates or other obstructions so that the vertical cylinder is divided into chambers. However, the emulsion of the nitrating product with the washing agent must be maintained until its discharge from the washing cylinder. For this reason, a stirring vane must be moved in each chamber by means of a vertical shaft or so much compressed air must be supplied that the emulsion is maintained during its passage through the cylinder.

If only a washing agent such as a soda solution is used, a single washing vessel is quite sufficient for obtaining a stable nitrated product. If however, several washing agents are to be used behind one another, just as many washing columns must be arranged successively.

The accompanying drawing explains the new process with reference to an example: The vessel 1 is of a cylindrical shape and is divided into the chambers 3 by the perforated plates 2. The acid nitrating product passes through the distributor 4, the washing liquid through pipe 5 and the compressed air through pipe 6 into the lowest chamber where the emulsion is formed which is now mixed with air and passes in a frothy condition to the overflow pipe 7 whence it is discharged in a small separating apparatus. The compressed air escapes

with the formed carbonic acid through the hook or cover 8.

I claim:

Process of continuously washing liquid esters of nitric acid, which comprises emulsifying the same with a washing agent maintaining the emulsion in an extended slowly flowing body for some time, locally agitating to maintain the emulsification but avoiding an intermingling of the freshly introduced acidulous ester with the already de-acidified portions.

In testimony whereof I affix my signature.

ARNOLD SCHMID.
